UNITED STATES PATENT OFFICE.

JUSTUS A. TRAUT, OF NEW BRITAIN, CONNECTICUT, ASSIGNOR TO THE STANLEY RULE AND LEVEL COMPANY, OF SAME PLACE.

DESIGN FOR A TOOL-HANDLE.

SPECIFICATION forming part of Design No. 26,464, dated December 29, 1896.

Application filed October 3, 1896. Serial No. 607,806. Term of patent 14 years.

To all whom it may concern:

Be it known that I, JUSTUS A. TRAUT, a citizen of the United States, residing in New Britain, in the county of Hartford and State of Connecticut, have invented and produced a new and original Design for a Tool-Handle, of which the following is a specification.

This invention relates to a design for tool-handles.

10 In the drawings accompanying and forming part of this specification, Figure 1 is a side elevation of a tool-handle, showing my design applied thereto. Fig. 2 is a transverse section of the same, the section being taken in line *a a*, Fig. 1.

Similar characters designate like parts in both figures of the drawings.

The leading features of my design consist in a tool-handle having symmetrical concave 20 grooves with rounded end walls closing the same at each end, said grooves being located intermediate the ends of the handle, and in

a trefoil located adjacent to one end of the groove and near an extremity of the handle.

2 and 2' designate, respectively, symmetrical grooves or concave depressions in opposite sides of the tool-handle *H*, adapted to hold various measuring or other tools, and 3 designates a trefoil figure shown located near one end of the handle, with its lower leg in 30 symmetrical alinement with the longitudinal axis of the groove 2 or 2'.

In connection with the leading features of my design I may also employ a narrow strip 4, of ornamental material, at one edge of the 35 handle, by which an enhanced effect is produced.

Having described my invention, I claim—
The design for a tool-handle, substantially as shown and described.

JUSTUS A. TRAUT.
